UNITED STATES PATENT OFFICE

112,791

DESIGN FOR A FISHHOOK

James C. Sailors, Jasper, Ala.

Application June 8, 1938, Serial No. 77,661

Term of patent 7 years

To all whom it may concern:

Be it known that I, James C. Sailors, a citizen of the United States, residing at Jasper, in the county of Walker and State of Alabama, have invented a new, original, and ornamental Design for a Fishhook, of which the following is a specification, reference being had to the accompanying drawing, forming part thereof.

Figure 1 is a top plan view of a fishhook, showing my new design.

Figure 2 is a view in side elevation thereof.

The characteristic features of the design reside in the fishhook shown having a rearwardly extending substantially flat triangular formation

which has its side edges merging with the side walls of the body member and which projects rearwardly between the forward ends of the hooks, as shown.

I claim:—

The ornamental design for a fishhook, as shown and described.

his
JAMES C. X SAILORS.
